United States Patent Office

Des. 231,815

Patented June 18, 1974

231,815

CABINET

Robert Levine, Roslyn, N.Y., assignor to Capehart Corporation, New York, N.Y.

Filed June 9, 1972, Ser. No. 261,573

Term of patent 14 years

Int. Cl. D6—04

U.S. Cl. D6—151

FIG. 1

FIG. 2

FIG. 3

FIG. 1 is a front perspective view of a cabinet showing my design;

FIG. 2 is a top plan view; and

FIG. 3 is a view in end elevation thereof.

The side not shown is a mirror image of the side shown.

I claim:

The ornamental design for a cabinet, as shown and described.
